UNITED STATES PATENT OFFICE.

ERNEST MALIHA, OF BROOKLYN, NEW YORK.

COMBINATION CABINET.

Application filed April 1, 1922. Serial No. 548,571.

To all whom it may concern:

Be it known that I, ERNEST MALIHA, a citizen of Syria, residing at the city of New York, borough of Brooklyn, in the county 5 of Kings and State of New York, have invented certain new and useful Improvements in Combination Cabinets, of which the following is a specification.

This invention relates to storage or display cabinets and has particular reference 10 to cabinets for the storing of various commodities in a manner that will insure complete seclusion or housing of such commodities while at the same time rendering it easy 15 for any of the commodities to be made accessible.

Among the objects of the invention is to provide a cabinet of any suitable size or 20 general design and constructed of any suitable materials, the same being provided with a multiplicity of upright panels arranged for the supporting and carrying of various articles or items on their inner walls, said panels being so constructed or arranged 25 as to be swung outward around vertical axes in order to present the commodities either to view or within easy reach.

A further object of the invention is to provide a cabinet having a plurality of vertical panels of uniform width and having 30 means for swinging said panels in such a manner that they may constitute in effect the side walls of a casing, whether the outer or the inner surfaces of the panels are presented to view, the casing being adapted to 35 be substantially closed in either position of the panels.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a detail perspective view showing the normal appearance of the cabinet with the casing closed.

Fig. 2 is a vertical central section of the same on the line 2—2 of Fig. 3.

Fig. 3 is a horizontal section on the line 55 3—3 of Fig. 2.

Fig. 4 is a horizontal sectional detail of

the panel manipulating means, as from the line 4—4 of Fig. 2.

Fig. 5 is a horizontal section on a plane just above that of Fig. 3 and illustrating the 60 side walls or panels of the casing swung partially open.

Referring now more specifically to the drawings, I show my device as including a base 10, a pedestal 11, and a casing 12 supported in any suitable manner upon the upper part of the pedestal.

The casing 12 comprises a bottom 13, shown as of regular hexagonal form, and at 14 is a top similarly shaped. The bottom 70 and top are held in fixed spaced relation to each other by suitable stationary binding or stay rods 15 extending through corresponding holes in the bottom and top and having shoulders 16 and 17 bearing against the 75 upper surface of the bottom and the under surface of the top, respectively, both ends of the rods being screw threaded for the accommodation of nuts 18 for binding the bottom and top in firm position against said 80 shoulders and to give an ornamental finish to the cabinet. The nuts for this purpose are shown as of rounded or spherical form.

Harmonious with the shape of the bottom and top and to make a casing substantially 85 in the form of a regular prism, which in the form shown is hexagonal, I provide a corresponding number of panels 19, shown as of flat formation and of equal width. Each panel is so shaped or molded as to 90 include a hinge member or hub 20 preferably of smooth cylindrical form, having a central vertical hole therethrough and through which one of the aforesaid rods 15 passes. The panels 19 are substantially co-extensive 95 in vertical length with the height of the space between the bottom and the top of the casing, and the width of each of the panels is such that its free edge swings or lies close to the hub of the next adjacent 100 panel. In other words, the appearance is that the flat portion of each panel fits snugly between two adjacent similar cylindrical columns. Each panel however, except as soon to be stated, is free to swing 105 outward from its closed position as shown in Figs. 1, 2, and 3 so as to occupy any desired position around the axis of the rod 15 which supports it.

The panels are adapted to carry on either 110 face, shown as on the inner face, any suitable holders, receptacles, or devices for carrying,

supporting, or displaying any desired articles or commodities, either for convenient use, display purposes, or the like. For example or for the purpose of illustration merely, I indicate a cabinet designed especially for a man's use, the same being provided with means on the inner faces of the panels for supporting cigars on shelves or racks 21 and 22, ink at 23 and a writing pen at 24, playing cards at 25, a box of matches at 26, and cigarettes at 27. From what has been stated however it will be understood that these receptacles may be variously arranged and for holding other commodities. Supported upon the top 14 is an ash tray 28 of any suitable construction.

Within the casing and supported in any convenient manner upon the upper surface of the bottom 13 is a drawer 29 adapted to be drawn outward as shown in Fig. 5, as by pulling upon a knob 30. This drawer is shown fitted with a sliding lid 31. The drawer is shown guided between and held in place by rabbeted rails 32 fixed to the bottom 13. This drawer may be employed for retaining cigars, game apparatus, or any other desired articles.

Any suitable means may be provided to manipulate the panels 19, either for opening or closing the same or for holding them all in a similar uniform position with relation to the other parts of the casing. To this end I attach to the upper end of each hub 20 a pinion 33, the connection between the pinion 35 and the hub being through pins 34 projecting into holes 34'. The pinion and the hub will be understood to be freely rotatable around the rod 15 which supports them. Since the casing is symmetrical with respect to its vertical center or axis, the pinions are equally spaced from said center and so are adapted to be actuated or controlled simultaneously by means of a master gear 35 through which a shaft 36 passes and is secured and to the upper end of which is fixed a handle or knob 37. The shaft 36 is journaled in a bearing sleeve 38 secured in the center of the top 14. It will be understood that the master gear is in constant mesh with all of the pinions 33, and so when the master gear 35 is rotated around the axis of the

shaft 36, as in a clockwise direction, looking down upon the device, the panels will all be swung simultaneously and to an equal extent in a counter clockwise direction as indicated by the dotted line 40, Fig. 3. For the opening of the drawer 29 the panels must of course be stopped at a mid position as in Fig. 5, but otherwise the panels may be swung so as to practically change positions with one another as indicated by the aforesaid dotted line 40. Hence it follows that if the panels are all swung open to their fullest extent, what normally is the outside would become the inside wall of each panel, and so the articles for use or display carried by the normally inside faces thereof will be supported then directly upon the outside. Obviously the smooth normally outside surfaces of the panels may be ornamented or may carry advertising matter if desired. The several panels are so supported upon the shoulders 16 as to swing with an almost imperceptible degree of friction, but the combined friction of all of the panels and parts co-operating therewith is sufficient to hold the panels in whatever position they may be left after the knob or handle 37 is actuated, so that the panels will be self retained in position automatically.

I claim:

1. In a cabinet of the character set forth, the combination of a bottom, a top, a series of symmetrically spaced stationary stay rods extending between the top and the bottom, screw threaded means to clamp the rods to the top and bottom surfaces of the top and bottom of the cabinet for holding them in fixed spaced relation, and a series of panels mounted upon said rods and movable around the same.

2. A device as set forth in claim 1 in which each panel is provided with a pinion, and a master gear is provided having constant mesh with all of the pinions for controlling the action of all of them simultaneously, each panel having a hub along one edge and the pinion pertaining thereto being fixed to one end of the hub.

In testimony whereof I affix my signature.

ERNEST MALIHA.
